(57) **CLAIM**

The ornamental design for a suitcase foam insert, as shown and described.

DESCRIPTION

FIG. 1 is a top perspective view of a suitcase foam insert in accordance with the present invention.

FIG. 2 is a front view thereof. The rear view is a mirror image of the front view.

FIG. 3 is a left side view of a suitcase foam insert in accordance with the present invention. The right side view is a mirror image of the left side view.

FIG. 4 is a top plan view of a suitcase foam insert in accordance with the present invention.

FIG. 5 is a bottom plan view thereof; and,

FIG. 6 is a top perspective view of a suitcase foam insert in accordance with the present invention.

Broken line illustration of environmental structure in the drawing is not part of the design sought to be patented.
